LABEL AND FOIL WIPING APPARATUS

Albert C. Tess, Ramsey, N. J., assignor to Edward Ermold Company, New York, N. Y., a corporation of New York

Application December 20, 1949, Serial No. 133,968

9 Claims. (Cl. 216—57)

1

This invention relates to label applying machinery and more particularly, to improved method and mechanism for use in automatic labeling machines for wiping labels into engagement with curved or cylindrical surface articles, such as bottles, jars, cans and the like.

In applying labels or decorative foils to containers, it is conventional to utilize one or more wiper elements mounted, for example, on reciprocating carriers which move the wiper elements into engagement with the unattached label to press or wipe the label upon a surface of the container. Where the label is to surround a portion of a bottle, usually the neck portion, a pair of laterally reciprocating wiper elements in the form of freely rotatable, long bristle brushes have been made to reciprocate in sequence past the trailing edge of the moving bottle, engaging first one free end of the label and wiping it against the bottle and then, with the second brush, wiping the other free end in like manner from the opposite side.

Such method of wiping offers the least wiping action at that end of the label where it is most required. Also, the action of the second wiper, due to the free rotation thereof, is such that the label is pressed more than wiped onto the bottle surface. Thus quality of the finished work is dependent largely on the pressure exerted by the wiper element on the label and container. With some types of labels, however, and particularly those finished with a heavy varnish coat, flagging or peeling of the label may occur or the label may be otherwise marred from excessive radial pressure.

In accordance with the invention, a label or foil applying mechanism is provided for overcoming the deficiencies of the conventional method and more effectively affixing the protective or ornamental label about the container or other article.

This is accomplished by providing mechanism affording positive rotary movement to at least one of the opposed wiper elements, which movement is supplemental to and concurrent with oscillatory or reciprocatory motion thereof. By virtue of the oscillatory motion or bodily translation in a curvilinear path, the wiper element is forced to follow a path partially around the container in such manner that a substantially uniform pressure is exerted over a larger portion of the label. In addition, the added and attending rotary movement enables the attainment of a definite "wiping" action by the wiper element.

The direction of the supplemental rotary move-

2

ment imparted by the novel mechanism to one wiper is opposite to that which would occur should the wiper be allowed to freely rotate about its axis while in engagement with the label. This action also tends to draw the label taut by wiping while lightly pressing the label into contact with the container.

The invention may be more readily understood by reference to the following description of a representative embodiment, taken in conjunction with the accompanying drawings, in which:

Figure 1 is a view in side elevation of a portion of a bottle labeling machine incorporating the improved wiper mechanism as seen in the direction of movement of the bottles;

Figure 2 is a view in vertical section taken along the line 2—2 of Figure 1;

Figure 3 is a top view of a portion of the labeling machine showing in an inactive position a portion of the mechanism for actuating the wiper elements and with a bottle and its unaffixed label approaching the wipers;

Figure 4 shows a portion of the mechanism of Figure 3 with the first wiping element at the completion of its operative engagement with the label and the bottle neck; and

Figure 5 shows a portion of the mechanism of Figure 3 with the first wiper returned to its initial position and the second wiper in action, completing the application of the label to the bottle.

The drawings show a novel, wiper-actuating mechanism formed according to the invention and isolated from a complete labeling machine such as that shown in the U. S. patent of Edward Ermold, No. 1,871,677, to which reference may be had for a detailed description of a labeling machine to which the present invention may be applied.

Referring to Figure 2, a line of bottles 10, suitably spaced from each other, is passed in the direction of the arrow 13 by conventional and continuous conveying mechanism (not shown) between a pair of juxtaposed wiper elements 11 and 12, which may comprise long-bristled brushes, for example. In timed relationship to the movement of the bottles and prior to the actuation of the wiper elements to engage the bottle neck, a label, sheet or foil or the like, L, is placed against the bottle by suitable applying means not shown, and clamped to the bottle by suitable gripper means 14, shown in Figure 3, but not forming part of the invention. The label L, which is made to partially envelop the bottle

neck, is pre-gummed along its two inside vertical edges.

As the bottle with its unaffixed label continues to move in the direction of arrow 13, the flagging end of the label L, engages the first wiper element 11, and is partially wrapped around the bottle by virtue of the linear translation of the bottle by the conveyor. When bottle and label have passed the center of wiper 11, the wiper is actuated to move at right angles to the path of the bottle and across the trailing edge thereof to the approximate position shown in Figure 4, thus completing the wipe of the first free end of the label. The bottle and label, continuing their travel through the machine, engage wiper element 12 which is in its initial (or retracted) position and the other end of the label is partially wrapped around the bottle due to the feeding movement of the conveyor. In timed relation to the movement of the bottle, the wiper element 12 is then actuated by mechanism described below and caused to swing about the axis of pin 22 across the trailing edge of the bottle while in addition being positively rotated about its own axis in a direction opposite that which it would have if allowed to roll freely over the surface of the bottle.

Thus, a positive wiping action is obtained, and since the brush travels along an arc in the direction of the movement of the bottle, a substantially uniform pressure is exerted by the wiper on the label throughout its wiping cycle. Also, because the arcuate movement of the brush causes it to follow the bottle in a limited amount along its line of feeding movement, it is possible to effect wiping of the label beyond the point of tangency of a plane at right angles to the line of feed of the bottle with the trailing edge thereof. This results in highly effective application of so-called "all-around" labels.

The wiper elements 11 and 12 are actuated sequentially in timed relation to the movement of the bottle through the machine by means of cams (not shown) which rock pivotally mounted bell-crank levers 15 and 16 which in turn reciprocate slide bar carriers 17 and 18, respectively, in opposite directions through corresponding pin and slot connections 17' and 18', all as described in said Patent No. 1,871,677. It should be noted that although the actuating mechanism described in the said patent may be similar to that utilized herein, the timing of the respective movements should be modified according to this disclosure in order to produce the correct wiping actions.

The cylindrical wiper element 11 is freely rotatively mounted on a post 19 depending vertically from the slide bar carrier 17 and is reciprocated therewith laterally of its axis of rotation.

Instead of being rotatively mounted on an axis which is fixed with respect to the slide bar carrier 17, as in the case of wiper 11 and the prior art, the wiper element 12 is mounted upon a vertical post 20 which is suspended from one end of a lever arm 21, the other end of which is supported for pivotal movement about a vertical pin 22 by a stationary, cantilever hanger arm 23. The hanger arm 23 is endwise affixed by suitable means such as a bolt-secured block 24 to a vertical, stationary column 25. Thus, the wiper element 12 may be swung or revolved about the pin 22 with the lever arm 21 as a radius.

A roller 20' mounted on the upper end of the vertical post 20, which carries the wiper element 12, extends upwardly to be laterally embraced by the arms of a yoke member 26 secured to the

underside of the slide bar carrier 18. Thus, as the slide bar carrier 18 is reciprocated, it swings the wiper element 12 about the center 22 through the driving action of the yoke member 26. It should be noted that within the limits of the reciprocation of the slide bar carrier 18 the arcuate displacement of the wiper element 12 is such that the component of movement in the direction of feeding motion of the bottle increases as the wiper engages the trailing edge of the bottle and moves partially about the surface thereof.

The actuation of the respective wiper elements 11 and 12 is such that they move in opposite directions and engage the bottle neck in timed relationship so that the free ends of the labels are successively wiped against the bottle, thereby enabling the wiper elements 11 and 12 to effect a complete wrap of the label about the neck of the bottle as described.

It will be seen from Figure 5 that as the wiper element 12 engages and rolls on the label the spreading bristles tend to slide the label L about the bottle neck. This action, unmodified, could cause bunching or other undesirable effects in the applied label. Also, if the wiper and bottle are moving in paths which are substantially mutually perpendicular, wiping pressure decreases as the wiper approaches the end of the label and it is impossible to effectively wipe a label beyond the trailing edge of the bottle.

To modify these possible undesirable effects a radius arm 27 is secured to the freely rotatable, upright shaft 20 which carries the wiper element 12. The free end of the radius arm 27 is joined by means of a pivotally connected link 28 to a stationary lug 29 affixed to the cantilever hanger arm 23, the radius arm 27 and link 28 comprising a constraining linkage. This constraining linkage is so adjusted that as the wiper element is bodily displaced laterally with respect to its axis by the action of the slide bar carrier 18 on pivot arm 21, it is concurrently rotated about its own axis. The direction of this rotation, as the wiper is moved into engagement with a bottle, is indicated by the arrow 30 of Figure 5, and is such that the absolute motion, i. e., relative movement with respect to the bottle surface, of that portion of the wiper which is in engagement with the label is increased. This rotary motion of the wiper tends to drag the bristles over the label, thus providing the positive wiping action described above.

It will be apparent, therefore, that the tendency of the spreading bristles of the wiper element 12 to push or slide the label in a counter-clockwise direction will be materially decreased. Furthermore, by appropriate design of the mounting linkage, including the pivot arm 21 and slide bar carrier 18, the portion of the wiper element 12 in engagement with the bottle surface may be made to exert more or less radial pressure on the label thus enabling control of any tendency to mar the label. This controlled, oscillatory arcuate movement of the wiper element 12 is useful in controlling the amount of pressure exerted on the receding bottle and label, and maintaining the desired pressure until the end of the label has been affixed to the bottle, even though the label encompasses the bottle for somewhat more than 360°, or beyond the trailing edge. Moreover, the amount of positive rotation of the wiper 12 may be controlled by appropriate design of the constraining linkage including the radius arm 27 and connecting link 28, thereby to govern the degree of frictional wiping

energy imparted to the label to insure its tautness or smoothness.

While a specific embodiment has been described above, the invention is not intended to be limited thereto, but is susceptible of numerous changes in form and detail. For example, both wiper elements may be provided with positive driving means for imparting positive rotational movement in various amounts thereto simultaneously with the usual lateral displacement. Furthermore, the supporting linkage for the wiper elements may be changed in several respects without departing from the spirit of the invention as set forth in the appended claims.

I claim:

1. In a machine for labelling objects, conveyor means for moving said objects through the machine, means for wiping a label upon a surface of the object, including a wiper element, a mounting for said wiper element permitting rotary movement thereof about an axis, a carrier for said mounting providing for movement of the mounting to displace the wiper element laterally of said axis of rotation and in a direction substantially transversely of the direction of conveyor movement, and positive driving means for simultaneously rotating the wiper element about said axis and displacing said mounting and wiper element laterally with respect to said axis, said rotary and lateral movements being in directions supplementing one another to wipe the label upon a surface of the object.

2. In a label-applying machine, in combination, means for conveying objects to be labelled through said machine, means for positioning a label adjacent a surface of the object, a pivot arm disposed laterally of the line of bottle movement, a wiper member rotatably carried by the free end of said pivot arm, and actuating means for oscillating said arm about the pivot and for rotating the wiping member in timed relation to the movement of the object through the machine, thereby to carry said wiper member into engagement with said label to cause the label to be wiped onto a surface of the object by a combination of rotary and translatory movement.

3. In a machine for applying a label to a given surface, a wiper element having a label-engaging portion, means for bodily displacing said wiper element to engage said label to press the latter against the given surface by movement relatively thereto, and positive driving means for rotating said element simultaneously with the displacement thereof, thereby to increase relative movement between the label and the label-engaging portion of the wiper during the wiping operation.

4. In a labelling machine including work conveying means and means for positioning a label adjacent a surface of the work, a wiper element, means supporting said wiper element for rotation about an axis, a carrier for said supporting means providing for bodily displacement of the wiper element in a direction lateral with respect to the axis of rotation and transversely of the direction of conveying movement, and unitary actuating means for simultaneously rotating the wiper element about said axis and for displacing the wiper element, thereby to press the label against a surface of the work, with the bodily displacement of the wiper as well as the rotational movement thereof affording relative movement with respect to the surface of the work.

5. In a machine for applying a foil to a bottle to surround the neck portion thereof and having means for positioning a foil adjacent the bottle

neck prior to being wiped upon the surface, the combination of conveyor means for moving said bottle through the machine, a first wiper element, means for displacing said element in translation along a given line substantially transversely of the direction of conveyor movement to engage and partially wipe the foil upon the bottle neck, a second wiper element having a foil-engaging portion and an axis of rotation, means for displacing said second wiper element in translation in directions substantially transversely of the direction of conveyor movement and opposing those of said first wiper element and in timed relationship thereto, thereby to engage and wipe the foil upon the bottle neck at a point spaced from said first wiper element, and positive driving means for rotating said second wiper element about said axis in a direction such that the foil-engaging portion thereof is displaced relatively to the label surface at a rate exceeding that caused by said lateral translation of the second wiper.

6. In a bottle labelling machine, a wiper element for pressing a label into engagement with a bottle surface, said wiper having an axis of rotation, means supporting said wiper and permitting oscillatory movement about an axis spaced from said axis of rotation and rotary movement about said axis of rotation, driving means for oscillating said wiper, a radius arm secured to said wiper, link means joining the free end of said radius arm to a stationary point, said radius arm and link means providing a positive driving connection for rotating said wiper simultaneously with the oscillatory movement thereof.

7. In a bottle labelling machine having bottle-conveying means and means for positioning a label adjacent a surface of said bottle prior to being affixed thereto, in combination a first label wiping element and means for bodily displacing the wiping element to engage said label in timed relationship to the movement of the bottle through the machine by the conveying means, a lever arm, a second label wiping element supported by said lever arm for rotation about an axis, means pivotally supporting said lever arm at a point spaced from the axis of rotation of said wiping element, a radius arm connected to rotate said second wiping element about said axis, a stationary support, a link connecting the free end of said radius arm to the stationary support, a reciprocating member, and operative driving connections between said reciprocating member and said second wiping element, whereby by reciprocation of said member causes the second wiping element to partake of concurrent revolutionary and rotary motion in engaging the label.

8. In a bottle labelling machine as set forth in claim 7 wherein the operative driving connections between said reciprocating member and said second wiping element comprise a shaft portion substantially coaxial with the axis about which said wiping element is rotated, and a yoke member laterally embracing said shaft and secured to said reciprocating member.

9. A machine for applying a label to the surface of a container including in combination, means for conveying said container through the machine, a first wiper element having a label-engaging portion, means for bodily displacing said wiper element in a given first direction to engage the label to press a portion of the same against the surface of the container adjacent the trailing edge thereof with respect to the con-

veyor motion, a second wiper element having a label-engaging portion, means for bodily displacing said second wiper element in a direction having a component of motion substantially opposite to said first direction to engage said label to press the same against the surface of the container adjacent the trailing edge thereof, said wiper elements being displaced in timed relationship.
